United States Patent Office.

WILLIAM H. ROACH, OF HARRISVILLE, OHIO.

Letters Patent No. 101,408, dated March 29, 1870.

IMPROVED WASHING-MACHINE.

The Schedule referred to in these Letters Patent and making part of the same.

To all whom it may concern:

Be it known that I, WILLIAM H. ROACH, of Harrisville, in the county of Harrison and State of Ohio, have invented a new and useful Improvement in Washing-Machines; and I do hereby declare the following to be a clear, exact, and full description of the same, sufficient to enable others skilled in the art to which this invention appertains to fully understand and use the same, reference being had to the accompanying drawing making part of this specification, and in which—

Figure 1 is a top or plan view of a washing-machine, illustrating my invention.

Figure 2 is a central longitudinal section thereof in line $z z$, fig. 1.

Figure 3 is a detached perspective view of the guide-rollers and arms which play between the same.

Similar letters of reference indicate corresponding parts in the several figures.

This invention has reference to an arrangement of parts whereby a horizontally-reciprocating rubber is guided so as to secure a free, un retarded movement, and whereby the said rubber is adapted to adjust itself vertically to conform to the bulk of the clothes beneath it.

This invention consists in the combination and construction of the tub and rubbers, and their various connections, to form an improved washing-machine, as will be hereinafter more fully described.

In the drawings—

A represents the box or tub, mounted on suitable legs, a .

On the bottom of this tub I arrange a series of transverse rollers, B, which lay side by side, with sufficient intervening spaces to allow the water to pass freely between them.

A space, b , unoccupied by the rollers, is left at each end of the tub.

From one end of the tub there arises standards, C, forming bearings for two transverse rollers, D, which are placed one above the other, sufficient room being left between them for the free longitudinal motion of the arms E, which carry the rubber F.

This rubber is merely a block or slab of suitable material, having its lower face grooved transversely.

It is connected to the arms E by the rigid hangers c.

It will be seen that the rubber is thus suspended perpendicularly from said arms, by means of which it can be reciprocated horizontally, depressed, or raised.

One end of each arm is formed into a handle, d, by means of which handles the rubber can be readily operated, or moved from one position to another.

$d d$ are circumferential grooves formed in the rollers D, in order to guide the arms E in their forward and backward motions.

These arms are connected rigidly together by suitable cross-pieces, f.

It will be seen that greater leverage is obtained by this arrangement.

The rollers D serve as a fulcrum for the arms E, and hence the operator can apply great pressure to the clothes during the rubbing or washing process.

It is obvious that, in order to secure the effective, unobstructed operation of the rubber F, the arms E must be held against lateral movement at two longitudinal points; otherwise whatever lateral vibration the arms should undergo would throw the sides of the rubber F out of parallelism with the sides of the tub, and thus cause the rubber to bind.

In my machine this obstruction of the motion of the rubber is obviated, in consequence of the holding of the arms E against lateral movement at somewhat distantly-removed longitudinal points, namely: where the said arms pass through the grooves $d d$ of the rollers D D, and where the rigid hangers c c join said arms E, the rubber F being fitted in a sufficiently snug manner between the pieces B' B', in which the rollers B have their bearings.

It will be seen that the axes of the rollers D D are in an inclined, but nearly vertical, plane, the effect of which arrangement is to enable the arms E to be freely vibrated vertically, sufficiently to admit of the withdrawal of the rubber from the tub, which could not be accomplished if the rollers D D were situated in a vertical plane.

As fine articles require to be carefully rubbed, and as the appearance of the clothes may be sometimes improved after they have been subjected to action of the rubber F, I have made provision for hand-washing by fluting or corrugating one end of the tub, as seen at h.

In order to render the wash-board h accessible, the lid or top-piece e, which prevents the water from splashing out, is secured by dovetailing, so that it may be slid out of position, as shown in fig. 1.

Having thus described my invention,

What I claim as new, and desire to secure by Letters Patent, is—

As my improvement in washing-machines, the construction and arrangement of the friction-rolls D D, with their circumferential grooves or guides $d d$, levers E E, in combination with the uprights c c, rubbers F and B, corrugated end h, with slide e, over-hanging piece e, and with box A, all as described, and for the purpose set forth.

WILLIAM H. ROACH.
